UNITED STATES PATENT OFFICE.

JACOB RUBIN, OF CHARLESTON, WEST VIRGINIA.

TIME-CONTROLLED ELECTRIC SWITCH.

1,371,935.

Specification of Letters Patent. Patented Mar. 15, 1921.

Application filed February 6, 1919. Serial No. 275,420.

To all whom it may concern:

Be it known that I, JACOB RUBIN, a citizen of Poland, residing at Charleston, in the county of Kanawha and State of West Virginia, have invented new and useful Improvements in Time-Controlled Electric Switches, of which the following is a specification.

The object of the invention is to provide in conjunction with an electric circuit closing and opening device a time controlled mechanism having means for closing and keeping closed for a specified interval of time the electric circuit closing and opening device. To carry this object into effect, the apparatus is so constructed that it may be used with a conventional form of clock movement, the hour hand moving parts of which are operatively connected with a rotatably mounted disk which carries an adjustable tripping finger operatively engageable with the circuit closing and opening device. The adjustment of the trip means makes for the operation of the circuit closing device at any desired time and through any desired interval of time.

A further object of the invention is to provide an apparatus or mechanism of the above mentioned character, which is simple in construction, durable and effective in operation and inexpensive to manufacture.

Other and further objects appear in the following description, wherein the invention is set forth in detail.

A specific embodiment of the invention as illustrated and described is adhered to, but to this embodiment it is not to be restricted. The right is reserved to make such changes or alterations as the actual reduction to practice may suggest, in so far as such changes or alterations are compatible in spirit with the annexed claims.

In the accompanying drawings:

Figure 1 is a front elevational view of the invention.

Fig. 2 is a central vertical sectional view through the structure of Fig. 1.

Fig. 3 is a top plan view of the structure of Fig. 1.

Fig. 4 is a perspective view of one of the tripping arms used in conjunction with the device.

As shown, the invention is designed to be operatively connected to a conventional form of clock movement, the minute and hour spindles 1 and 2 of which are shown

and operatively connected by the gear train generally designated 3 as is customary with such movements. The remainder of the clock mechanism being not essential to an understanding of the invention, is not shown herein, but this mechanism is designed to be carried in an appropriate casing, only the front wall 4 of which is shown. Both the minute and hour spindles 1 and 2 project through this front wall, the minute spindle being journaled in the hour spindle, as is usual, and the latter being journaled in the wall 4, having attached to it exterior to the wall the gear 6. This gear 6 meshes with an idle pinion 7 rotatably mounted on a stud 8 set in the front wall 4. The pinion 8 in turn meshes with a gear 9, which is twice the diameter of the gear 6 so that the angular velocity of the former will be one-half that of the latter in order that the gear 9 may make one revolution in twenty-four hours, the gear 6 being connected to the hour spindle, obviously making two revolutions in twenty-four hours.

The gear 9 is formed on the front face with a relatively narrow annular portion 10 and on the front face of this annular portion there are formed the radially disposed slots 11 uniformly spaced around the annular portion 10, and being 24 in number, so that there will be one slot for each of the twenty-four hours.

The gear 9 on the front face between its peripheral edge and the outer or peripheral edge of the annular portion 10 carries the indicating marks 12 for the purpose of indicating the 12 hours anti and post meridian.

The gear 9 is rotatably mounted on a stud 13 fixed in the front wall 4 and this stud 13 carries a pointer 14. Thus when the gear 9 revolves it moves relative to the pointer and the indications 12 pass the pointer obviously in a clockwise direction.

Carried by the front wall 4 and to one side of the gears 6 and 9 although positioned in close proximity to both there is a circuit closing and opening device and this device comprises a base block 15 made of insulating material and carried on brackets 16 which are secured to the front wall 4. This base block carries the two hinged posts 17 (the circuit closing device being a double pull switch) to which the switch blades 18 are pivotally attached at one end. The remaining ends of these switch blades are interconnected by an insulated cross bar 19

and the base 15 carries a pair of flat springs 20 secured to the base and bearing against the under edges of the blades tending to keep them out of contact with the clips 21 which are carried by the block 15. The blades 18 may be forced down between the clips 21 against the pressure of the springs 20 and the gear 9 carries the means to effect this necessary pressure. This means comprises a trip member formed with a shank 22 which is rectangular in cross section, this shank being diminished to fit in any one of the slots 11 formed in the annular portion 10, in which it is secured by a screw 23, which passes through either one of the holes 24 formed in the shank and threads into either one of the holes 25 formed in the annular portion 10 of the bottom slots 11. The object of the peculiar arrangement of holes shown is to provide for the adjusting of the trip to increase or diminish its radial extent. Obviously if the screw 23 is inserted through the uppermost hole in the shank 22 and threaded into the outer hole 25 the trip member has its greatest radial extent if the screw passes through the upper hole 24 in the shank and through the inner hole 25 in a slot 11, the radial extent of the trip is reduced. If the screw passes through the lower hole 24 of the shank 22 and threads into the inner hole 25 of the slot 11, the radial extent of the trip is still further reduced. Aside from the shank 22 the trip is formed with an arcuate arm 26 at the lower end of the shank and extending laterally in one direction therefrom and is formed with an inclined nose portion 27 carried at the bottom of the shank and extending laterally in the other direction. The nose portion 27 of the trip member initially engages the circuit closing device so that the switch forming part of the latter may be depressed for engagement with the clips 21. To reduce the resistance of this operation to a minimum, the cross bar 19 of the switch carries two upstanding supports 28 between which there is rotatably mounted an anti-friction roller 29 with which the nose 27 engages and with which the arcuate portion 29 maintains contact to keep the switch depressed. Obviously the switch will remain depressed as long as the arcuate portion 26 maintains contact with the roller 29 and the arcuate portion 26 may, therefore, be made of any length de-

sired, but in the present instance it is the intention to make this arcuate portion of such a length that when the trip member is set in the distance of greatest radial extent the angular measurement of the arcuate portion will be equal to the angular measurement between any two adjacent slots 11. Thus when the trip member is set to close the switch it will keep the same in closed position for one hour, since the angular velocity of the gear and perforce the angular velocity of the annular portion 10 is one-twenty-fourth of a revolution per hour.

In the event that it is desired to keep the switch closed for a longer period than one hour, a second trip member—or a third one if desired—may be operatively positioned in succeeding slots, as indicated by dotted lines in Fig. 1, so that the combined length of the arcuate portions may make for the keeping of the switch closed for as many hours as there are arranged trips in a gang. Again, trips may be positioned at different points around the annular portion 10 to arrange for closing the switch at certain times and when it is desired to position the trips so that they may not effect the operation of the switch, their radial extent may be reduced in the manner above described.

The spring 20 serves always to keep the switch open except when it is engaged by the trips.

The invention having been described, what is claimed as new and useful is:

A mechanism of the kind described comprising a rotatably mounted wheel having means for operatively connecting it to a driving mechanism, a circuit opening and closing device, the said wheel being provided with an annular portion in one face of which there is formed a plurality of radially disposed slots, trip members each embodying a shank engageable in any one of the said slots and having an arcuate arm extending laterally in one direction and an inclined nose portion extending laterally in the other direction but at an acute angle to the shank, and means detachably securing the shanks in the said slots, whereby the trip members may be arranged in gangs indiscriminately for engagement with the circuit opening and closing device.

In testimony whereof I affix my signature.

JACOB RUBIN.
